UNITED STATES PATENT OFFICE.

LAZARD KAHN, OF HAMILTON, OHIO, ASSIGNOR TO F. & L. KAHN & BROTHERS, OF SAME PLACE.

COOKING-STOVE.

SPECIFICATION forming part of Letters Patent No. 371,892, dated October 18, 1887.

Application filed December 30, 1886. Serial No. 222,958. (No model.)

To all whom it may concern:

Be it known that I, LAZARD KAHN, of Hamilton, Butler county, Ohio, have invented certain new and useful Improvements in Cooking-Stoves, of which the following is a specification.

My invention pertains to cooking-stoves provided with roasting-spits; and the improvement will be readily understood from the following description, taken in connection with the accompanying drawings, in which—

Figure 1 is a perspective view of the oven portion of a cooking-stove illustrating my improvement; and Fig. 2, a plan of the contiguous portions of the spit and arm, the bearing in the arm being shown in section.

In the drawings, A indicates the oven of a cooking-stove; B, the door thereof; C, the usual hinge of the door; D, a segmental shelf or plate lying upon the bottom of the oven and pivoted therein and adapted to swing in and out of the oven; E, the pivot of the shelf, where the shelf is articulated to the oven-bottom, the pivot in the present case presenting an upwardly-open square axial socket; F, a turn-latch upon the oven-door, catching into a slot in one edge of the shelf, this catch serving as a means by which the shelf may be locked at will to the door, so as to move in and out as the door is closed and opened in the common manner; G, a bearing seat formed with or secured to the wall of the oven over the pivot E, such bearing-seat being intended to receive a removable journal-bearing, the seat being illustrated as being formed with dovetailed retaining-jaws; H, a journal-bearing removably held in the bearing-seat, the axis of the bearing coinciding with the axis of the pivot E, and the bearing being removable from its seat by an upward motion, which withdraws it from the dovetailed jaws of the seat; J, a mast journaled in the bearing H and free to move upward therein, and having its foot squared and stepped in the pivot-socket of the shelf; K, an arm reaching outward from the mast and provided at its outer end with a horizontal bearing; L, a spit projecting horizontally at right angles to this arm and provided at its inner end with a horizontal journal engaging the bearing in the free end of the

arm; and M, the supporting attachment between the end of the arm and the end of the spit, the same consisting of the horizontal journal upon the end of the spit and the horizontal bearing on the end of the arm, as clearly shown in Fig. 2, whereby the spit may be rotated upon its axis.

A fowl or joint may be impaled upon the spit. The weight of the fowl or joint will tend to depress the spit, and thereby exert a lever-like action upon the bearing at the end of the spit, and thus create a certain amount of binding-friction between the spit-journal and its bearing in the arm. This friction is sufficient to prevent the automatic rotation of the spit in its bearing on the arm in case the roast should be somewhat heavier upon one side than upon the other; but the spit and roast may be readily turned by hand, and the friction referred to will serve in retaining the roast in any new position of rotation into which it may be adjusted. When the arm K is in the position indicated in the drawings, the roast is practically out of the oven and in a position for convenient inspection and dressing, after which the roast may be pushed inward, the arm taking up a position against the oven-wall, while the spit with its roast will take a position at right angles to the oven-wall. The roast with the spit and arm and mast may be lifted vertically out of engagement with the bearing H, and the entire spit apparatus thereby removed from the oven; and in putting the roast upon the spit the spitting may be done before putting the spit apparatus into the oven.

When not in use, the spit parts may be laid away, including the removable bearing H, which may be removed from the bearing-seat, thus leaving the wall of the oven substantially free from obstructions.

By means of the square-socket engagement of the foot of the mast with the pivot of the shelf the spit with its roast is automatically moved in and out of the oven with the shelf, whereby a dripping-pan placed upon the shelf may follow the movements of the roast and catch the drip therefrom at all times. The latch F serves, as usual, to connect the door with the shelf, so that the shelf moves out and

in with the opening and closing of the door, and obviously the entire arrangement results in the roast and dripping pan being swung in and out of the oven by the mere manipulation 5 of the door, while at the same time the latch may be disconnected, so that the door may be opened for the inspection of the roast without withdrawing either the roast or shelf.

I claim as my invention—

- 10 1. A bearing with a vertical axis, a piece journaled therein, and a horizontal spit connected with such journal-piece and adapted for oscillation upon the axis of such vertical bearing, combined substantially as and for the purpose set forth.
- 15 2. An oven, a vertical bearing at the wall thereof, a mast journaled in such bearing, an arm projecting horizontally from such mast, and a spit projecting horizontally at right angles from such arm, combined substantially as and for the purpose set forth.
- 20 3. An oven, a segmental shelf pivoted upon the floor thereof and adapted to be oscillated into and out of the oven, a spit, and a support for said spit journaled in the oven, combined substantially as and for the purpose set forth.
- 25

4. An oven, a segmental shelf pivoted to the floor thereof, a spit, and a support for the spit having a journal disposed in the axis of the pivot of said shelf, so as to oscillate with the shelf, combined substantially as and for the purpose set forth.

5. An oven, an oven-door, a segmental shelf pivoted to the floor of the oven, a spit, and spit-support connected with and arranged to oscillate with said shelf, and a latch upon the door adapted to engage said shelf and oscillate said shelf and spit as the door is opened and closed, combined substantially as and for the purpose set forth.

40 6. Oven A, bearing-seat G upon the wall thereof, bearing H, separably engaging such seat, mast J, engaging such bearing, arm K, and spit L, combined substantially as and for the purpose set forth.

LAZARD KAHN.
